UNITED STATES PATENT OFFICE.

CRENO P. BETTENGA, OF MARSHALLTOWN, IOWA.

DISINFECTING HEN'S NEST.

Application filed April 7, 1927. Serial No. 181,800.

My invention relates to improvements in disinfecting hens' nests, and the objects of my improvements are first, to provide a disassemblable housing for a nest having a portal shaped to prevent roosting of a fowl thereon, and second, to supply as an adjunct of the detachable bottom of the housing a removable container for a volatilizable repellent composition for repelling insects, and which also may serve the purpose of an artificial nest egg under a setting hen.

Other improvements will be referred to in the following description and the appended claims.

In the annexed drawings, Fig. 1 is a perspective view of my improved hen's nest as suspended on a fixed support. Fig. 2 is a vertical longitudinal section of the same on an enlarged scale, and Fig. 3 is a detail perspective view of the detachable bottom of the device including the repellent holder.

The numeral 7 denotes a wall or other erect supporting structure, and on which the nest housing is suspended spaced from the ground or floor below. The housing is composed of sections, connected by slip joints and secured together thus to be disassemblable for storage or transportation in little compass or volume, which is important, as transportation charges are commonly based on volume rather than on the weight of the articles carried. The housing has a top plate 3 inclined forwardly to shed rain as also to prevent roosting of fowls thereon. This plate has comating reversed marginal edges 4 at front and sides to receive outturned marginal parts slidably and separably of the two side wall plates 2. The housing has no back-plate, and has an open bottom to be closed by a detachable bottom closure to be described.

Apertured hanger-bars 5 are bolted to the rear upper part of said housing to be removably suspended upon headed pins or screws 6 fixed in the wall 7. A cross-bar 18 is fastened across the back of the housing spaced from its lower end.

The front plate or wall 1 of the housing is slidably marginally connected to the abutting outturned edges of the side plates 2 in the same manner as at 4 to the top plate 3, all stiffened also by having outturned marginal edges where not so slidably connected.

The front plate 1 has an open portal 8 whose threshold 10 has a medial upwardly

directed projecting part 9. Spaced in parallel from the front plate at a level with said threshold is a step bracket-bar 12 fixed to the forward ends of side arms 11, the latter medially pivoted to the side walls 2 on 60 pintles 13, and having their rear ends stopped from upward movement from the horizontal by projecting bolt ends 14 in said side walls. The medial projection 9 with sloping side edges is only high enough to prevent the 65 roosting of a fowl on the threshold 10, without preventing the fowl from passing to and fro through the portal from or to the step bracket 12, the side portions of the threshold 10 being wide enough to afford support for 70 the fowl's feet on either side of said projection.

I have supplied a detachable bottom for said housing, particularly shown in Figs. 2 and 3. This is an elastic metal plate 15 having a number of spaced transverse crimps 19 directed upwardly, which crimps render the plate hingedly bendable between the crimps so as to be shaped into a segment of a hollow cylinder with concavity directed 80 upwardly as a hollow nest, and having separated side edge projections 15' directed upwardly spaced from the abutting inner side walls of the housing to provide ventilating openings. The rear marginal edge of the 85 plate 15 is hooked over at 17 to be suspended on the rear cross-bar 18 detachably, while the forward edge of the plate is provided with spaced hooked parts 16 to be supported upon the lower threshold parts 10. 90

The numeral 20 denotes an open end container for a filling 26, which may be a porous material impregnated with a repellent substance which will be readily volatilizable by a moderate heat such as that of a hen in 95 said nest sitting across the container, in which relation the container serves the further function of a medial artificial nest egg. The container may be of any other suitable shape and size, the one shown having been 100 thoroughly and successfully used in practice. The container shown is in the shape of an elongated trough 20 of inverted U-shape, and may have end projections 22 bent downwardly to prevent escape of the filling material 26. Small apertures 23 are provided along the top of the container for exudation 105 of the volatile fumes from the repellent substance therein when warmed by the heat of the hen's body, which approximates 104 de- 110

grees F. These fumes repel or kill mites or other vermin which commonly infect or penetrate the hen's feathers and down.

The container 20 may be secured to the bottom plate 15 by bolts and nuts 24 and 25, or in any other desired manner, and the side walls of the container may be notched at 21 to receive a raised crimp 19, dividing the middle of the nest into shallow compartments to receive a layer of soil with a top dressing of straw or the like, but the top of the container should be raised above the tops of the crimps for the purpose of an artificial nest egg, touching the body of a hen setting on the nest above the container.

The bottom 15 may be readily detached from the housing for cleansing and return. It should be noted that the curved segmental bottom 15 with its crimps 19 is so elastically bendable between said crimps, that when the housing parts are disassembled for shipping or storage, the bottom 15 may be bent over flatly to be piled in a tier with the other wall plates, in a small low compact bundle and secured together in a minimum space. When taken from the bundle, the bottom 15 will elastically react to resume its former curvate shape ready for use. As so shaped and arranged any number of these nests may be positioned in horizontal or superposed rows suspended on a wall, for convenient and economical employment.

Having described my invention, what I claim as new, and desire to secure by Letters Patent, is:

1. A device of the character described, comprising in combination, top, front, side and bottom members detachably connected in a hollow knockdown housing structure, one of said members having a portal whose threshold has a medial raised projection which prevents a fowl from roosting on the threshold with horizontal top and sloping sides meeting horizontal parts.

2. A device of the character described, consisting of a hollow housing one wall of which has a portal with the middle part only of its threshold raised with horizontal top spaced high enough to prevent the roosting of a fowl on the threshold, while affording side foot-holds for the fowl to step upon securely.

3. A device of the character described, comprising a hollow housing having a portal and a removably connected concave bottom closure, said closure being an elastic transversely crimped plate with its crimps directed upwardly and which plate reacts to be planar when disassembled.

4. A device of the character described, comprising a hollow housing having a portal and a removably connected bottom closure spaced from the side walls only of the housing and having separable connections at front and rear to the housing, said closure being an upwardly concaved transversely crimped elastic plate which reacts to a planar shape when disassembled.

5. A device of the character described, comprising a hollow housing having a portal and having an open bottom, a closure for said open bottom detachably end connected to the housing and spaced from its side walls only, and a medial longitudinal elongated hollow apertured inverted U-shaped receptacle for an insect repellent composition volatilizable by heat and removably secured on said closure to also serve as a simulated egg device.

6. A device of the character described, comprising a hollow housing having a front portal, said housing having a detachably connected bottom closure shaped from an elastic plate with raised transverse crimps and edge projections spaced from the adjacent side walls of the housing, and said closure also being shaped as a segment of a cylinder when elastically bent between the crimps, and when disassembled as a planar body.

7. A device of the character described, comprising a ported housing having a detachable bottom closure, said closure being concaved cylindrically upwardly, and an inverted U-shape container for a repellent composition, having top apertures and open ends, and detachably secured medially longitudinally along said closure to also serve for nest egg purposes for a setting fowl bestriding it.

In testimony whereof I affix my signature.

CRENO P. BETTENGA.
